UNITED STATES PATENT OFFICE.

JOSEPH L. HERZOG, OF NEW ROCHELLE, NEW YORK.

FOLDABLE LINK-BUTTON.

1,367,141.

Specification of Letters Patent.

Patented Feb. 1, 1921.

Application filed December 11, 1918. Serial No. 266,182.

To all whom it may concern:

Be it known that I, JOSEPH L. HERZOG, a citizen of the United States, residing in the city of New Rochelle, county of West-
5 chester, and State of New York, have invented certain new and useful Improvements in Foldable Link-Buttons, of which the following is a specification.

My invention relates to buttons, commonly 10 but not necessarily made up as articles of jewelry, adapted for use as cuff buttons, collar or shirt studs, or for any other purpose where a quickly insertible or removable button is desired; and is of the type comprising a pair of buttons or button heads proper and an interposed connecting link member having its ends pivoted or joined to the respective heads so that one or both of said heads may be folded flat against the 15 link when it is desired to insert the button into or remove it from the garment, and folded transversely to the link after the button has been inserted so as to hold the garment between the heads. When both heads 20 are folded against the link, they and the link will all lie in a substantially common plane.

My improvement comprises a foldable button of the type described in which the button-head proper has but two pieces, one 25 or both of which is resilient, joined together, preferably, at their outer edges and holding between them the pivotal end or pintle of the link. This link end or pintle is shaped so that, working co-operatively with the inner faces of the head, said head tends to be positively held in either of its two above-specified limiting positions, *i. e.*, flat against the link or transverse thereto.

My invention will be better understood by 30 referring to the accompanying drawings in which Figures 1 to 10 inclusive show the invention embodied in a preferred form of cuff button, Figs. 11 to 13 show the invention in a modified form of cuff button, and Figs. 14 to 17 show the invention in still another modified form of cuff button.

In these drawings, Fig. 1 represents a side view of the button with the heads in open or garment retaining position; Fig. 2 35 represents a view similar to Fig. 1 but with both heads folded ready for insertion in the garment; Fig. 3 represents a view taken from the top of Fig. 2; Figs. 4 and 5 represent respectively a rear view of, and a central section through, the back plate of the

button head; Fig. 6 represents the connecting link as seen in Fig. 1 but with the button heads detached; Fig. 7 represents a rear view and Fig. 8 a central section through the front plate of the button head; Fig. 9 40 represents, on an enlarged scale, a central section through one end of the button taken at right angles to the link pivot or pintle with the button-head in folded position; Fig. 10 is a view similar to Fig. 9 but with 45 the button-head half-way between the folded and open position; Fig. 11 shows a central section, parallel with the pivot pintle, through one of the ends of a modified form of the invention; Fig. 12 represents a view 50 taken from the rear of Fig. 11; Fig. 13 represents a perspective view of one end of the link used in the form of the invention shown in Figs. 11 and 12; Fig. 14 represents a side or edge view of one end of another 55 modified form of cuff button; Fig. 15 represents a rear view of Fig. 14; Fig. 16 is a central section, on an enlarged scale, parallel to the pivot pintle through one end of the button of Figs. 14 and 15; and Fig. 17 is a 60 view similar to Fig. 16 but showing the front plate of the button-head before the rear plate has been put in place.

Referring to the drawings, Figs. 1 to 10 inclusive, 1 represents the button as a whole 65 including two similar circular heads, 2, 3, and a link, 4, pivoted to and connecting said heads. The heads may be, as illustrated, identical in size and one or both may be provided with any desired ornamentation. Or, the head members may be of different sizes and one or both may be differently shaped, as, for instance, elliptical, 70 square, or the like.

Each head comprises the following parts, 75 preferably stamped from sheet metal, namely, an outer cap or front plate, 5, having a peripheral flange, 6, and an inner or back plate, 7. A short diametral but eccentric slot, 8, is cut out of this back piece, and, 80 also, preferably, diametrically but at right angles thereto, the material is pressed outwardly at 9, so as to provide bearings for the ends of pivot pintles, 10, which are formed at each end of the link 4, and project therefrom.

Link 4 is preferably of flattened cross-section, in this case, that of an ellipse, and bent or curved in the plane of the longer axis thereof to which longer axis, at each 110

end of the link, the pintles 10, are respectively perpendicular. The pintles are disposed, however, upon opposite sides of the link; they are, also, of square cross-section having faces respectively parallel with and transverse to the longitudinal axis of the link.

In forming the slot 8, in back plate 7, a part of the metal is bent inwardly, as 10 shown in Figs. 4 and 5, to constitute a tongue, 11. So, also, at the other or central end of slot 8, the metal is pressed outwardly, as at 12, in line with one side of the bearings 9, so as to serve as a stop for positively limiting the movement of the link 4 when the button-head, 2, is unfolded with respect thereto.

Link, 4, may, also, be readily formed and shaped from sheet metal by a single punching 20 operation.

In assembling the button an end of link, 4, is held adjacent to the rear side of back plate, 7, (i. e., top of Fig. 4 and right of Fig. 5) and turned so that pintle, 10, lies in 25 the plane of slot 8; the link end may then be thrust through the slot. The link should then be again turned so as to bring the pintle, 10, adjacent to or facing tongue, 11, with the pintle ends in the bearings, 9. The link 30 and back plate being held in this stated position, the back plate should now be inserted within the cup formed by flange, 6, upon the rear of front plate, 5. A suitable press operation, readily understood by those skilled 35 in the art, may now be employed to fold the edges of flange, 6, over upon the back plate, thus permanently uniting them, and to simultaneously press tongue, 11, back into the plane of the back plate, thus bringing the 40 tongue end closely adjacent the pintle and substantially closing the unfilled opening in the back plate. The same operation may then be repeated with reference to the other end of the link and its head. Or, the tongue, 45 11, may first be pressed back into the plane of the back plate before the pressing operation to unite the front and back plates, is undertaken.

The bearings, 9, should be of such depth, 50 with relation to the thickness of the pintle, 10, that, with the latter in either of its two limiting positions (as shown in Fig. 1 as compared with Figs. 2, 3, and 9, e. g.), the front and back plates, 5, and, 7, will be held 55 slightly separated, thus insuring that either of these limiting positions will be maintained until the button-head is positively swung upon the pintle, either against or away from the link, as the case may be.

With the button-head unfolded or setting 60 across the link, 4, (Fig. 1), the link will be abutted against by the stop, 12, so that its further movement upon its pintle with respect to the button-head will be prevented.

65 In folding or unfolding the button-head

about the pintle with respect to the link, the front and back plates are positively forced farther apart during the first 45° of rotation against the resiliency of said plates; while, during the remaining 45°, the resiliency of the plates will act with and assist the positively applied force.

Either the front or back plate may be 70 relatively stiff and unyielding, thus placing all the effective resiliency in the remaining plate; or, the effective resiliency may be divided between the two plates to any desired extent by suitably determining the two plates either as to thickness, hardness, or some other qualifying factor.

80 The form of the invention shown in Figs. 11 to 13 is similar to that shown in Figs. 1 to 10 except that the button-heads are outwardly convexed instead of flat. This is accomplished by suitably and similarly 85 shaping both the front and back plates, 5, and, 7, and by giving the faces of the pintles, 10, a corresponding curvature. The mode of assembly and operation is the same as for the button of Figs. 1 to 10.

90 The form of the invention shown in Figs. 14 to 17 differs substantially from that of Figs. 1 to 10 only in that the flange, 6', corresponding to flange 6 of Figs. 1 to 10 and of Figs. 11 to 13, is formed upon the back 95 of the front plate at a distance from the outer edge instead of actually at said edge.

95 My improved button may, of course, have either or both of the button-heads engraved or ornamented or set with stones, as may be preferred.

The improved button is extremely neat in appearance and very simple and easy to manufacture, involving as it does merely very usual and ordinary punching and 105 pressing operations. Its construction is, also, especially desirable in that it is purely mechanical requiring neither soldering nor brazing.

Another advantage of my improved button 110 is that but three different pieces enter into its construction, viz., the front plate, the back plate, and the connecting link.

I may, of course, if I prefer, substitute 115 an anchored, non-foldable head for the foldable head, at one end of the link, this type of link button being well-known in the art. In this case, the tongue, 11, may be omitted and the opening in the back plate made just large enough to permit the link to pass 120 therethrough since the link end to be anchored will require no pintle, and may be passed through the opening in the back plate before the anchoring operation is performed.

125 While I prefer the use of the stop, 12, so as to compel the button-head to always fold upon the same side of the link, I may, by omitting the stop, permit the head to fold on either side of the link.

130 Other details may be varied within the

spirit of the invention and the scope of the following claims:

1. In a foldable link button, the combination of a two part head comprising a front plate forming the exposed and actual front of the head and a back plate connected with said front plate and forming the exposed and actual back of the head, at least one of said plates being resilient, a link and a terminal pintle lying between said plates whereby said head is pivotally mounted on said link, said pintle having a plurality of faces adapted for surface engagement with the inner surface of one of said plates whereby the head is fixed in its folded and unfolded position by the resiliency of said one plate.
2. In a foldable link button, the combi-

nation of a link, a terminal pintle forming part of said link and having a plurality of surfaces, and a two part head pivotally mounted on said pintle and comprising peripherally connected plates constituting the exposed and actual front and back of the head between which said pintle is located and coöperating with the surfaces thereof to fix said head in its folded and unfolded position, said plates being in substantial surface engagement with each other in said folded and unfolded positions of the head and being spread apart as said head swings to and from said positions.

In testimony whereof, I have hereunto set my hand.

JOSEPH L. HERZOG.
